CONVERSION OF CREOSOTE

Jacquelin E. Harvey, Jr., Atlanta, Ga., assignor of
one-half to Southern Wood Preserving Com-
pany, East Point, Ga., a corporation of Georgia

No Drawing. Application July 13, 1940,
Serial No. 345,443

2 Claims. (Cl. 196—53)

This invention relates to the joint production of solvents and wood preservatives from creosote.

Creosote is a wood preserving distillate recovered from tars of aromatic content and includes distillates of various boiling ranges, as for instance any of the creosotes noted in the following tabular data:

WOOD PRESERVING IMPREGNANTS

Specification

1. A. W. P. A.
  - a—up to 210° C., not more than 5%
  - b—up to 235° C., not more than 25%
2. A. W. P. A.
  - a—up to 210° C., not more than 1%
  - b—up to 235° C., not more than 10%
  - c—up to 355° C., not less than 65%
3. A. W. P. A.
  - a—up to 235° C., not more than 1½%
  - b—up to 300° C., not more than 16½%
  - c—up to 355° C., not less than 45%
4. A. W. P. A.
  - a—up to 210° C., not more than 8%
  - b—up to 235° C., not more than 35%
5. A. W. P. A.
  - a—up to 210° C., not more than 10%
  - b—up to 235° C., not more than 35%
6. A. W. P. A.
  - a—up to 210° C., not more than 5%
  - b—up to 235° C., not more than 15%
7. Prussian Ry.
  - a—up to 150° C., not more than 3%
  - b—up to 200° C., not more than 10%
  - c—up to 235° C., not more than 25%
8. N. P. V. & L. A.
  - a—5% at 162° C.
  - b—97% at 270° C.
9. S. P. S. S. O.
  - a—5% at 137° C.
  - b—95% at 257° C.
10. N. S. S. O.
  - a—I. B. P., 150° C.
  - b—5% at 205° C.
  - c—95% at 292° C.

By the process of the present invention, creosote is treated with hydrogen whereby to produce solvents of enhanced solvency and wood preservatives of added toxicity.

By the term enhanced solvency is meant the solvents of the present invention have a higher solvency than solvents extant of comparable boiling range; by the term added toxicity is meant that the wood preservatives of the present invention are higher in toxicity than the starting material.

Creosotes, the starting materials of the present invention, are characterized by a content of oxygenated organic compounds. The invention provides a process for the conversion of creosotes into solvents and wood preservatives, the conversion being brought about by subjecting the starting materials to the action of hydrogen while under the influence of catalytic material adapted to influence the decomposition of oxygenated organic compounds contained therein.

It was formerly discovered that creosotes containing oxygenated compounds could be subjected to the action of hydrogen whereby to convert them to solvents and newly formed wood preserving oils, the newly formed wood preserving oils being characterized by induced toxic properties. It is now discovered that the induction of toxicity in the newly formed wood preserving oils can be enhanced by effecting the conversion in the presence of catalytic material adapted to decompose said oxygenated organic compounds.

The following examples will show modes of practicing the present invention.

Example 1.—A high residue creosote boiling substantially 5% at 210° C. and less than 35% at 235° C. was subjected to the action of hydrogen at 420° C. and 300 atmospheres pressure. Catalyst used consisted of molybdenum sulfide and tin chloride. Time of reaction was substantially one hour. The beneficiated creosote was removed from the reaction zone and inspected and was found to have a considerable percentage distilling between 70° C. and 205° C. and said percentage had a solvency in excess of solvents currently on the market having comparable boiling range or ranges. The beneficiated creosote was distilled up to 205° C. with the distillate serving as a solvent of the present invention and the residue therefrom serving as the wood preservative of added toxic value as compared to the starting material. The induction of toxicity was enhanced because of the presence of the catalytic material that influenced decomposition of oxygenated compounds while under the influence of hydrogen.

The point of separation of said solvents and wood preservatives is not inflexible inasmuch as solvents of commercial acceptance have various end points and wood preserving oils of known and published specifications are of varying initial boiling points. Thus, inasmuch as the end points of the solvents of the present invention correspond substantially to the initial boiling points 55 of the wood preserving oils of the present inven-

tion, it is obvious that the point of separation may be varied as desired. As an illustration in the tabular data shown below are solvents and wood preservatives of accepted and published specifications, their end points and initial boiling points, respectively.

SOLVENTS

Identification:	End point
Benzol	120° C.
Toluol	150° C.
High flash naphtha	200° C.
Heavy naphtha	above 200° C.

WOOD PRESERVATIVES

Identification:	Initial point
A. W. P. A.	5% at 210° C.
A. W. P. A.	1% at 210° C.
A. W. P. A.	1½% at 235° C.
A. W. P. A.	10% at 210° C.
Prussian Ry.	3% at 150° C.
N. S. S. O.	150° C.
S. P. S. S. O.	92° C.
Carbolineum	270° C.

Thus, it will be seen that, among other things, the present process is adapted to provide treatment of creosote with hydrogen, as heretofore explained, whereby to provide a newly induced low boiling point which comprises the initial boiling point of the solvent, and said initial boiling point may be controllably held at any point, as for instance:

SOLVENTS

Identification:	Initial point
Benzol	78° C.
Toluol	100° C.
High flash naphtha	150° C.
High boiling crudes	175° C.
Heavy naphtha	150° C.
Plasticizers	160° C. and above

Or, solvents of special nature may be produced, as for instance solvents having lower initial boiling points than noted above.

The initial or low boiling point of the overall beneficiated creosote is controlled by intensity of process controls. Controls of lesser intensity producing higher initial boiling points and controls of greater intensity producing lower initial boiling points, for a given period of treatment.

Light tars of aromatic content derived from petroleum, or fractions thereof, because of their inordinately low carbon, low specific gravity and viscosity, are herein considered the equivalent of creosote; however, because of, at times, their inordinately high initial boiling point, recourse must be had for induction of wider ranges, as for instance by longer periods of treatment.

Example 2.—A petroleum aromatic tar, Conradson carbon of substantially 7, specific gravity substantially 1 and initial boiling point of in the order of 250° C. is subjected to the action of hydrogen while contacting a catalyst containing a material selected from the group consisting of halides, halogens, and derivatives thereof. Temperature of reaction was 400° C., pressure 200 atmospheres. Operation is continued until a low boiling point of substantially 200° C. is induced. The beneficiated material is cut at 235° C. to provide the solvent as the lower boiling fraction and the wood preserver of enhanced toxic value as the higher boiling fraction.

Example 3.—A creosote, for example a coal tar creosote derived from high temperature coke oven tar, and having little or no residue above 355° C., is subjected to the action of hydrogen while flow-

ing said creosote through a reactor, at a temperature chosen from between 300° C. to 600° C. and the flow of hydrogen or hydrogen containing gas less than 12,000 cubic feet per barrel of creosote, pressure chosen from between 20–600 atmospheres, and for such a length of time that the initial boiling point of resultant beneficiated creosote is in the order of 115° C., or lower; catalyst employed included a material selected from the group consisting of halides, halogens, and derivatives thereof. The beneficiated creosote is distilled to an upper limit of 375° C., if desired, if and when this high boiling point exists after treatment. However, distillate may be recovered by distillation to the point where no residue results in the distillate at 355° C. whereby to provide in the fractions boiling between 200° C. and 355° C. a wood preservative of enhanced toxic properties; also to provide a solvent boiling between the initial boiling point and 200° C. However, the product without distillation may be used.

Example 4.—Another mode of practicing the present invention is the production of solvents within the range of substantially 190° C. and 290° C. by treatment of creosote as hereinafter set forth. A creosote, as for instance, one boiling substantially between 235° C. and 350° C., or having some residue above 350° C. is subjected to the action of hydrogen while contacting a catalytic material composed of tin chloride and iodoform; flow of hydrogen in excess of 2,000 cubic feet per barrel feed, pressure 225 atmospheres, and for such a length of time as to produce in the product flowing from the reactor no substantial percentage boiling below 190° C. The beneficiated material is then distilled to an upper limit, as for instance to 280° C., the distillate serving as the superior solvent of the present invention, and the residue the wood preservative of enhanced toxic properties. The solvent, that is to say, the portion boiling substantially 190° C. to substantially 290° C. may be fractionated to provide various solvents, including high boilers, having plasticizing properties. The wood preservative resulting from said fractional cut may be used as such, or refined by distillation with residue therefrom being recycled or utilized as an article of commerce, as for instance a binder or plasticizer of enhanced value. The wood preservative because of its boiling range may be used as a substitute for carbolineums.

For use in conjunction with aforesigned catalytic material, other and hydrogenating catalysts may be employed. Especially effective are those of the eighth and sixth periodic groups, as for instance oxides and sulfides, separately or in admixture. Especially effective are the oxides and/or sulfides of molybdenum, tin, vanadium, tungsten, cobalt, or the like; promoted or not; supported or not, as for instance on gels; in admixture with other substances effective in hydrogenation, or not.

Pressures of in the order of 200 atmospheres and above are the preferred operating pressures at present; however, lower pressures may be used for practicing the invention. The preferred temperatures are chosen from the range above 300° C., however, lower temperatures may be used.

By the term *beneficiated* is meant the starting material at least once subjected to the action of hydrogen in accordance to the present invention.

Starting feeds include all creosotes, and their equivalents, refined in any manner, as for in-

stance by hydrogen, and at times such is preferred.

When carrying on the present process in a continuous manner, hydrogen flows are always held in excess of 2,000 cubic feet per barrel creosote treated, preferably, at times, in excess of 10,000 cubic feet, according to desired results.

In continuous practice the reaction zone may consist of a single reactor, a series thereof, a parallelism thereof, including a multiplicity thereof. The end products of the present invention may be produced by passing the starting material to a reactor for more or less refining reaction, thereafter with or without releasing gas pressure, to another reactor for final production of desired products.

Especially desirable as starting feeds are creosotes, or fractions thereof, at least once refined by hydrogen.

Example 5.—Instead of practicing the invention as shown in foregoing examples, the following procedure may be practiced: instead of treating the overall creosote at first, only high boiling fractions may be treated. A creosote, as for instance a high residue creosote, is distilled to recover the fraction above 355° C. as a residue. The residue is then treated with hydrogen in accordance with foregoing disclosures for either refining purposes or for actual production of products of the present invention. In the event the residue is merely refined, the treated residue may be blended with the stripped fractions and further subjected to the action of hydrogen for the production of products of the present invention.

By the term creosote in the specification and the appended claims is not meant any specific boiling range material; but included in meaning are materials of the boiling range of any natural creosote on the market or possible of manufacture and also shingle stain oils, or the like, and the refined creosotes.

"Aromatic tars" of petroleum origin are herein considered the equivalent of creosote because of the low carbon content of said aromatic tars of petroleum origin.

A convenient method for evaluating toxicity is in accordance with "Method of Conducting

the Tests," page 2, Technical Bulletin No. 346, March, 1933, "The Effect of Concentration on the Toxicity of Chemicals to Living Organisms." A convenient method for evaluating solvent power is by the well-known Kauri-Butanol number or the aniline point.

Minor changes may be made without departing from the spirit of the invention. In the claims affixed to this specification no selection of any particular modification of the invention is intended to the exclusion of other modifications thereof.

I claim:

- 15 1. In the rendering of high temperature coal tar creosote more toxic to wood destroying fungi, the process which comprises: subjecting said creosote to the action of hydrogen while contacting as catalytic materials molybdenum sulfide and tin chloride; carrying on the process at a temperature and pressure of at least 400° C. and 200 atmospheres, respectively; continuing the treatment for such a length of time as to provide newly formed low boiling fractions boiling at least as low as about 70° C.; and fractionating the treated material to separate sufficient fractions boiling below 210° C. to provide a material as an oil of the wood preserving type boiling not in excess of about 10% at 210° C. having a toxicity in excess of the parent material.
- 20 2. In the rendering of high temperature coal tar creosote more toxic to wood destroying fungi, the process which comprises: subjecting said creosote to the action of hydrogen while contacting as catalytic materials molybdenum sulfide and tin chloride; carrying on the process at a temperature and pressure of at least 400° C. and 200 atmospheres, respectively; continuing the treatment for such a length of time as to provide newly formed low boiling fractions boiling at least as low as about 70° C.; and fractionating the treated material to separate sufficient fractions boiling below 210° C. to provide a material as an oil of the wood preserving type boiling not in excess of about 10% at 210° C. having a toxicity in excess of the parent material.
- 25 30 3. In the rendering of high temperature coal tar creosote more toxic to wood destroying fungi, the process which comprises: subjecting said creosote to the action of hydrogen while contacting as catalytic materials molybdenum sulfide and tin chloride; carrying on the process at a temperature and pressure of at least 400° C. and 200 atmospheres, respectively; continuing the treatment for such a length of time as to provide newly formed low boiling fractions boiling at least as low as about 70° C.; and fractionating from the treated material a relatively low boiling distillate and a relatively high boiling distillate, said distillate last named being an oil of the wood preserving type boiling not in excess of about 10% at 210° C. and being further characterized by toxicity in excess of its parent material.
- 35 40 45
